UNITED STATES PATENT OFFICE.

HENRY F. ROONEY, OF RANDOLPH, MASSACHUSETTS, ASSIGNOR TO
CORNELIUS E. HALE, OF WALPOLE, MASSACHUSETTS.

VIBRATOR.

No. 821,831.

Specification of Letters Patent.

Patented May 29, 1906.

Application filed July 10, 1905. Serial No. 268,958.

To all whom it may concern:

Be it known that I, HENRY F. ROONEY, of Randolph, in the county of Norfolk and State of Massachusetts, have invented certain new and useful Improvements in Vibrators, of which the following is a specification.

This invention relates to means for imparting rapid vibratory motion to the applicator of a massage apparatus by the action 10 of a sliding device on a rod carrying the applicator, the said device being adapted to alternately grip and release the rod in rapid succession when moved lengthwise thereon, and thus impart to the rod and to the applicator thereon a series of vibrations.

The invention has for its object, first, to provide certain improvements relating to the sliding device or rod-vibrating slide, whereby 20 its efficiency is increased, and, secondly, to provide the rod with means for increasing the amplitude of the vibrations imparted to it by the slide.

To these ends the invention consists in the improvements which I will now proceed to 25 describe and claim.

Of the accompanying drawings, forming a part of this specification, Figure 1 represents an edge view of a vibrator embodying my invention. Fig. 2 represents a top plan view 30 of the same. Fig. 3 represents a section on line 3-3 of Fig. 2.

The same reference characters indicate the same parts in all the figures.

12 represents a metal rod which is preferably cylindrical and is preferably made of steel, although any other suitable metal may be used.

13 13 represent knobs or rounded enlargements at the ends of the rod, one of these 40 serving as a handle and the other as an applicator. The knobs may be alike, so that either may be used as an applicator.

With the rod 12 is engaged a rod-vibrating slide in which the chief portion of my invention is embodied. The said slide comprises a resilient hardened-steel strip bent to form parallel end portions or rod gripping and releasing members 14 14 and a curved connecting portion 17. Each of the members 14 has 50 an orifice 15, formed to surround the rod with a sliding fit. The intersection of the walls of the orifices with the sides of the members 14 forms angular jaws 16. When the members 14 are at right angles with the rod, they are

adapted to slide freely thereon; but when 55 they are tipped or inclined slightly from a position at right angles with the rod the jaws 16 bite or engage the rod and oppose movement of the members 14 along the rod.

The slide has oppositely curved or inclined 60 side portions 18 18, which constitute finger- rests, enabling the operator to apply pressure to the slide in directions oblique to the rod, this pressure tending to tip the members 14 into rod-gripping relation with the rod. 65

In operating the device the operator grasps one of the knobs in one hand, presses the other knob as an applicator against the body to be treated, and pushes the slide along the rod by pressure of a finger or thumb against 70 one or the other of the inclined rests 18, care being taken to press only the rest at the rear side of the slide. The pressure thus directly applied to the rear member 14 is yieldingly 75 imparted through the spring to the forward member, which alternately grips and releases the rod independently of the other member. It will be seen, therefore, that each member 14 has an independent rod-vibrating action, so that the rod is vibrated with greater 80 rapidity than would be possible if the members 14 were rigidly connected and compelled to operate in unison. To the end portions of the rod 12 are rigidly affixed arms 19, which are notched to engage the end portions of 85 helical springs 20. These springs extend parallel with the rod and are held extended and under tension by the arms with which their ends are engaged. I prefer to employ two springs, although one or any other desired number may be employed. The vibrations of the rod are communicated to the 90 springs 20. The vibrations of the springs add to the vibrations imparted to the applicator by the rod. 95

I claim—

1. A vibrator comprising a rod having an applicator, and a slide having two rod gripping and releasing members separated by an intervening space, and each having an orifice 100 the wall of which is in close sliding contact with the rod, and a spring connection between said members, whereby pressure applied to one member lengthwise of the rod is yieldingly communicated to the other member. 105

2. A vibrator comprising a rod having an applicator, and a slide having two rod grip-

ping and releasing members separated by an intervening space, and each having an orifice the wall of which is in close sliding contact with the rod, and a resilient shank yieldingly connecting said members, said shank having oppositely-inclined finger-rests.

3. A vibrator comprising a rod having an applicator, a rod-vibrating slide movable on the rod, and arms rigidly attached to the end portions of the rod, and one or more helical

springs connected at their ends with the said arms and maintained under tension between the same, said springs being vibrated by the vibrations of the rod.

In testimony whereof I have affixed my ¹⁵ signature in presence of two witnesses.

HENRY F. ROONEY.
